Primary Examiner — Derrick Holland*Assistant Examiner* — Jennifer O King(74) *Attorney, Agent, or Firm* — Kilpatrick Townsend & Stockton LLP(57) **CLAIM**

We claim the ornamental design for an electromagnetic field apparatus, as shown and described.

DESCRIPTION

FIG. 1 is a top, front and side perspective view of an electromagnetic field apparatus showing our new design;

FIG. 2 is a top, rear and side perspective view thereof;

FIG. 3 is a left side elevation view thereof; the right side elevational view is a mirror image of the left side elevational view; and,

FIG. 4 is a front elevation view thereof.

The broken lines shown represent unclaimed subject matter and form no part of the claimed design.
